CLAIM

The ornamental design for a combined stamp pad and container, as shown and described.

DESCRIPTION

FIG. 1 is an perspective view of a combined stamp pad and container showing my new design;

FIG. 2 is a top plan view thereof;

FIG. 3 is a side elevational view thereof, the opposite side being identical;

FIG. 4 is an end elevational view thereof, the opposite end being identical;

FIG. 5 is a bottom plan view thereof;

FIG. 6 is an perspective view of a second embodiment of FIG. 1;

FIG. 7 is a top plan view of FIG. 6;

FIG. 8 is a side elevational view of FIG. 6, the opposite side being identical;

FIG. 9 is an end elevational view of FIG. 6, the opposite end being identical; and,

FIG. 10 is a bottom plan view of FIG. 6.
